UNITED STATES PATENT OFFICE.

CHARLES MILLS, OF NEWTON, MASSACHUSETTS, ASSIGNOR, BY MESNE ASSIGNMENTS,
TO SACO-PETTEE COMPANY, OF NEWTON, MASSACHUSETTS, A CORPORATION OF
MASSACHUSETTS.

COILER-TUBE.

1,040,566.

Specification of Letters Patent.

Patented Oct. 8, 1912.

Application filed July 8, 1909. Serial No. 506,513.

To all whom it may concern:

Be it known that I, CHARLES MILLS, of Newton, in the county of Middlesex and State of Massachusetts, a citizen of the 5 United States, have invented a new and useful Improvement in Coiler-Tubes, of which the following is a specification.

Drawing frames are usually set up in gangs, a number of them being connected up 10 in a row with a common power shaft and means common to all the frames for distributing power to run the various drawing rolls and coiling and can rotating mechanism. Thus a number of slivers are acted 15 upon at once. The value of such a machine depends upon its certainty of operation, its evenness of wear and its simplicity of construction, this last feature being of particular importance because of the necessity for 20 keeping the moving parts clean, *i. e.* free of the lint and dirt which always exist when cotton is being treated.

My present invention relates to the coiler tube, its connections and operation, my purpose 25 being to simplify and reduce the amount of mechanism heretofore considered necessary and so arrange it as to reduce friction and at the same time strengthen the frame and prevent any undue lengthwise 30 strain on the shaft.

The rotation of the coiler tube has been accomplished heretofore by a horizontal shaft running the length of the machine and at suitable points carrying a gear which 35 engages one of a train of gears by which the necessary movement is given to the coiler tube gear. Such an arrangement is cumbersome because of the room which the train of gears requires. Moreover the larger 40 the number of gears used the greater is the possibility of accumulating fly and lint in the moving parts, however the parts may be carried. Such accumulation has to be removed and this requires shutting down the 45 machine and perhaps the removal of the gears themselves. A reduction therefore of the moving parts is one of importance both in the matter of first cost and also in the economical running of the machine, constant 50 production being required of it and hence as little stoppage for cleaning and repairing as may be. Moreover in the usual construction no especial provision is made to hold each shaft gear to its work and hence there 55 is a general tendency to give to the shaft

as a whole an endwise thrust which causes increased friction and wear upon the moving parts. It is to overcome this difficulty, reduce the number of moving parts, simplify the manner of cleaning and repairing, 60 and make a practically noiseless machine that my invention has been made as well as to strengthen the frame, and it consists in such a reduction, rearrangement and reconstruction of parts that a gear upon the driving shaft acts directly upon the coiler gear, with corresponding results pointed out below.

My invention will be understood by reference to the drawings in which is shown a 70 drawing frame isolated from its neighbors all of which, however, are alike except as an end frame will require a power pulley, etc.

Figure 1 is a section on line 1—1 of Fig. 75 2, showing also a portion of a can and also the sliver feeding mechanism. Fig. 2 is a plan of my coiler. Figs. 3 and 4 are sections on lines 3—3 and 4—4 of Fig. 2.

A is the coiler plate which is bolted to 80 the front of the frame B of the machine by bolts *a*. This plate is recessed at *b* to form a channel running the length of the entire machine in which is supported the driving shaft C which also runs the length of the 85 machine. A number of these coilers, usually five or six, are generally set up together, a single shaft driving them all. The shaft C is supported in a bearing D bolted to the 90 coiler plate by bolts *d*. A hole *d*¹ is provided in each bearing for purposes of lubrication. The coiler plate A is also recessed as at E to provide a cavity for a gear F, the cavity being sufficiently large to allow the 95 gear to be adjusted more or less lengthwise the shaft and being constructed to inclose the gear as much as possible from dust and yet allow an opening through which the fly, etc., may be brushed from it. It will be noted that these so called recesses are the 100 result of bows or arches formed in the frame which strengthen the frame. This is a matter of considerable importance because unless the frame is stiff, the machine is liable to vibrate unduly in mills where the floor is 105 subjected to considerable jar. The gear F is a spiral or skew gear. It is made fast on the shaft C by a set screw *f* and preferably is set up against the bearing D as shown so that the bearing takes whatever thrust is 110

given to the gear. Thus the thrust is distributed between the bearings on the several coilers instead of on the head of the shaft as heretofore.

5 G is the coiler tube which is mounted in the coiler plate A to rotate in the usual way. For this purpose a runway g is provided in the coiler plate and a rim or track g¹ is formed on the under side of the coiler tube 10 to fit therein. The periphery of the coiler tube is provided with a spiral or skew gear g² to be engaged by the gear F so that it shall be rotated thereby. I prefer that the teeth in these gears shall be at an angle of 15 45° so that the coiler gear may be rotated in either direction as the rotation of the parts backward may sometimes be useful in cleaning the machine or otherwise.

In connection with my improvement I 20 have shown only so much of the drawing frame as is necessary for the proper understanding of my invention, H, H being the calender rolls operated in the usual manner, J the clearer and K the trumpet arm carrying the trumpet k through which the sliver h² is drawn and fed through the tube proper 25 L and into the can M.

The simplicity of my invention is apparent. To remove the coiler tube from the 30 coiler plate it is only necessary to remove the usual cover and then lift out the tube. The reduction of parts together with the distribution of the thrust and the consequent reduction of friction reduces the noise of the 35 machine materially so that it may be called practically noiseless. The reduction of parts also reduces the cost materially both of the machine and of repairs.

What I claim as my invention is:—

40 1. In a drawing frame, a coiler plate, a coiler tube rotatably mounted on said coiler plate and having a skew gear on its periphery, a shaft running lengthwise of

said coiler plate and carrying a skew gear meshing with said coiler tube gear, each of 45 said skew gears being provided with teeth arranged at angles of substantially 45° to their respective axes, and a bearing for said shaft located on said coiler plate and engaging said shaft adjacent the gear thereon. 50

2. In a drawing frame, a coiler plate of substantially uniform thickness having a channel running lengthwise of said plate near its rear edge, in combination with a coiler tube carrying a spiral gear on its periphery and a shaft carrying a spiral gear in mesh with said coiler tube gear, said shaft being located in said channel and said channel being enlarged opposite the axis of 55 said coiler tube to receive said gear. 60

3. In a drawing frame, a coiler plate having a channel running lengthwise thereof, a shaft bearing attached to the upper surface of said plate and projecting outward into said channel, a shaft supported by said bearing in said channel, a spiral gear on said shaft, said channel being recessed to receive said gear, and a coiler tube carrying a peripheral gear in mesh with said spiral gear, 65 said coiled tube being mounted to turn in 70 said plate.

4. In a drawing frame, a coiler plate of substantially uniform thickness having a channel running lengthwise of said coiler plate near its rear edge whereby said coiler 75 plate is stiffened, and a cavity therein provided with a dust-clearing opening, in combination with a rotatable coiler tube having a gear on its periphery, and a shaft supported in said channel carrying a gear located in said cavity and in mesh with the gear on said coiler tube, as set forth. 80

CHARLES MILLS.
